UNITED STATES PATENT OFFICE.

GEORGE MILLER, OF PITTSBURGH, PENNSYLVANIA.

CLIPPER.

1,091,232.

Specification of Letters Patent. Patented Mar. 24, 1914.

Application filed June 18, 1913. Serial No. 774,335.

To all whom it may concern:

Be it known that I, GEORGE MILLER, a subject of the King of Hungary, residing at Pittsburgh, in the county of Allegheny and State of Pennsylvania, have invented certain new and useful Improvements in Clippers, of which the following is a specification, reference being had therein to the accompanying drawing.

10 This invention relates to clippers, and more particularly to that type used by barbers.

The primary object of my invention is to provide a pair of clippers, wherein novel 15 automatic means is employed for adjusting the shoe of the clippers relatively to the shear, whereby the clippers can be used to a greater extent than at present.

Another object of this invention is to 20 furnish clippers with a novel apron that positions the hair in the path of the clipping knives as the clippers are moved over the head.

A further object of this invention is to 25 furnish the clippers with a novel closed shoe that is gradually moved away from the shear as the clippers are moved over the hair, thereby permitting of the hair being cut extremely close when the clippers are 30 placed in operation and the length of the hair gradually increased as the operation of the clippers continues.

I attain the above objects by clippers that eliminate the necessity of a barber using 35 shears or scissors for trimming or cutting the greater part of the hair.

It is a well known fact that at the present time clippers are generally used upon the neck and that when the hair is to be simply 40 trimmed that the clippers can only be used for a short distance upon the neck. Clippers in accordance with my invention can be practically used to the crown of the head, as the clippers are automatically adjusted 45 whereby when first placed in operation the hair is cut very short and as the operation continues the hair is cut with the hair gradually increasing in length. The clippers can therefore be placed in the hands of 50 an inexperienced barber and used to a degree of certainty that permits of the hair being expeditiously trimmed or cut.

My invention will be hereinafter specifically described and then claimed, and reference will now be had to the drawings, 55 wherein:—

Figure 1 is a plan of the clippers, Fig. 2 is a side elevation of the same, Fig. 3 is a perspective view of a detached shield, Fig. 4 is a horizontal sectional view of a pawl member adapted to form part of the clippers, Fig. 5 is a side elevation of the clippers partly broken away and partly in section, Fig. 6 is a plan of the clippers partly broken away and partly in section, Fig. 7 is a perspective view of a detached bearing, Fig. 8 is a plan of an apron, and Fig. 9 is a side elevation of an adjustable shoe.

Further describing my invention in detail with reference to the accompanying drawings, wherein like numerals denote corresponding parts throughout: 1 denotes a clipper body having a stationary handle 2 and an oscillatory handle 3. The body 1 has the ordinary central post 4, shears or knives 5 and a stationary shoe 6. These parts are common to an ordinary pair of clippers and form no part of my invention.

Connected to the front side of the body 1 by screws 7 or other fastening means is a yoke 8 having the ends thereof provided with diametrically opposed bearings 9. The yoke 8 is provided with brackets 10 and at the ends of said brackets are vertical guides 11, said guides having dovetailed grooves 12 and shoulders 13 for a purpose that will presently appear.

Revolutionarily mounted upon the bearings 9 and retained thereon by nuts 14 or other fastening means are the hubs 15 of large pinions 16 and small pinions 17, said pinions being formed integral with the hubs 15, which are also toothed to provide pinions 18. The large and small pinions extend in proximity to the guides 11, as best shown in Fig. 6.

Mounted upon the post 4 is a spacing sleeve 19 and surrounding said sleeve is the hub 20 of a ratchet wheel 21. The ratchet wheel is hollow and the lower edges thereof are toothed to provide a circular rack 22 that meshes with the pinions 18.

Arranged in the hollow ratchet wheel 21 is a spiral band spring 23 that has one end thereof connected to a post 24, carried by the body 1 and the opposite end thereof connected to the hub 20 of the ratchet wheel.

Connected to the oscillatory handle 3 is a bifurcated support 25 and pivotally connected to said support, as at 26 is a pawl member 27 having a thumb piece 28. The pawl member 27 is segment-shaped in plan.

and has a groove 29 containing a plurality of pivoted spring pressed pawls 30 adapted to engage the ratchet wheel 21 and move said wheel in one direction, said pawls receding when the wheel is moved in the opposite direction.

Pivottally connected to the stationary handle 2 is a locking lever 31 provided with a pivoted tooth 32 that engages the ratchet wheel and prevents the ratchet wheel from rotating in one direction.

Arranged below the clipper body is an adjustable shoe 33 having fingers 34. The shoe 33 is supported by two vertical racks 35 and 36, said racks having tongues 37 slidable in the grooves 12 of the guides 11. The racks 35 and 36 mesh with the large pinions 16, as best shown in Figs. 1 and 2.

The rear end of the shoe 33 forms a casting 38 for a spring roller 39, constructed upon the principle of a curtain shade roller. The spring roller 39 has an apron 40 that extends longitudinally of the shoe 33, under a roller 41 carried by said shoe and has the end thereof attached to the stationary shoe 6, as at 42. As the adjustable shoe 33 is moved to and from the stationary shoe the apron 40 is wound and unwound from the spring roller.

Arranged upon the post 4 and supported by the spacing sleeve 19 is a shield 43 that has enlargements 44 providing clearance for the pinions 16. The shield also has an opening 45 providing clearance for the vertical rack 35. This shield is employed to prevent hair from interfering with the operating mechanism and as a guard for the ratchet wheel 21 and the pinions 16 and 17.

In operation, an oscillatory movement of the handle 3 intermittently moves the ratchet wheel 21 and as said ratchet wheel is intermittently moved a similar movement is imparted to the pinions 18, 16 and 17. With the pinions 16 meshing with the racks 35 and 36, the adjustable shoe 33 is gradually lowered, consequently as the clippers are moved over the head the hair is cut first very short and then gradually increasing in length, until the adjustable shoe 33 has been moved as far from the stationary shoe 6 as the racks 35 and 36 permit. Then, when the pawl member and the lever 31 are manually shifted, the ratchet wheel is recessed, and the spring within said ratchet wheel immediately revolves the same and restores the adjustable shoe 33 to a normal position in engagement with the stationary shoe 6.

By placing the racks 35 and 36 against the shoulder 13 of the guides 11 said racks will mesh with the pinions 17, consequently the speed of the shoe shifting mechanism can be increased.

It is thought that the operation and utility of my invention will be apparent without

further description and while in the drawings there is illustrated a preferred embodiment of the invention, it is to be understood that the structural elements are susceptible to such changes, as in the size, shape and manner of assemblage as fall within the scope of the appended claims.

What I claim is:—

1. A hair clipper comprising a stationary shoe, a clipping mechanism mounted thereon, an oscillatory handle for actuating said mechanism, a vertically adjustable shoe, a spring controlled roller carried by the adjustable shoe, an apron winding upon the roller and extending at the bottom of the adjustable shoe and further extending through said adjustable shoe and fixedly secured to the stationary shoe and winding on and off the roller during the adjustment of the stationary shoe, vertically movable means for adjusting said adjustable shoe, and a shifting mechanism operated in one direction by said handle for shifting said vertically movable means in one direction, said shifting mechanism including a self-contained element for shifting said vertical movable means in the opposite direction.

2. A hair clipper comprising a stationary shoe, a clipping mechanism mounted thereon, an oscillatory handle for actuating said mechanism, a vertically adjustable shoe, a spring controlled roller carried by the adjustable shoe, an apron winding upon the roller and extending at the bottom of the adjustable shoe and further extending through said adjustable shoe and fixedly secured to the stationary shoe and winding on and off the roller during the adjustment of the stationary shoe, a pair of vertically movable racks, one connected to one side of the adjustable shoe and the other connected to the other side of the adjustable shoe forwardly thereof, and a shifting mechanism operated in one direction by said handle for shifting said racks in one direction, and said shifting mechanism including a self-contained element for operating the mechanism in the opposite direction for moving said racks in the opposite direction.

3. A hair clipper comprising a stationary shoe, a clipping mechanism mounted thereon, an oscillatory handle for actuating said mechanism, a vertically adjustable shoe, a spring controlled roller carried by the adjustable shoe, an apron winding upon the roller and extending at the bottom of the adjustable shoe and further extending through said adjustable shoe and fixedly secured to the stationary shoe and winding on and off the roller during the adjustment of the stationary shoe, a pair of vertically movable racks, one connected to one side of the adjustable shoe and the other connected to the other side of the adjustable shoe forwardly thereof, a shifting mechanism oper-

ated in one direction by said handle for shifting said racks in one direction, and said shifting mechanism including a self-contained element for operating the mechanism in the opposite direction for moving said racks in the opposite direction, and means carried by said handle and engaging with said shifting mechanism to prevent operation of said mechanism in a direction other than that operated by the handle.

4. A hair clipper comprising a stationary shoe, a clipping mechanism mounted thereon, an oscillatory handle for actuating said mechanism, a vertically adjustable shoe, a spring controlled roller carried by the adjustable shoe, an apron winding upon the roller and extending at the bottom of the adjustable shoe and further extending through said adjustable shoe and fixedly secured to the stationary shoe and winding on and off the roller during the adjustment of the stationary shoe, a pair of vertically movable racks, one connected to one side of the adjustable shoe and the other connected to the other side of the adjustable shoe forwardly thereof, a shifting mechanism operated in one direction by said handle for

shifting said racks in one direction, and said shifting mechanism including a self-contained element for operating the mechanism in the opposite direction for moving said racks in the opposite direction, and means capable of engaging with said shifting mechanism for increasing the speed of the racks.

35

5. A hair clipper comprising a stationary shoe, a clipping mechanism carried thereby, an oscillatory handle for operating said clipping mechanism, an adjustable shoe movable to and from said stationary shoe, a winding apron carried by the adjustable shoe and having one end fixedly secured to the stationary shoe, means actuated by said handle for imparting movement to the adjustable shoe in one direction, and a normally locked means adapted when released for shifting said shoe in the opposite direction.

40

In testimony whereof I affix my signature in the presence of two witnesses.

GEORGE MILLER.
